UNITED STATES PATENT OFFICE.

JOSEPH A. STEINMETZ, OF PHILADELPHIA, PENNSYLVANIA.

FIRE-EXTINGUISHING APPARATUS.

1,102,812.

Specification of Letters Patent.

Patented July 7, 1914.

Application filed May 8, 1914. Serial No. 837,147

To all whom it may concern:

Be it known that I, JOSEPH A. STEINMETZ, a citizen of the United States, residing at Philadelphia, in the county of Philadelphia and State of Pennsylvania, have invented 5 certain new and useful Improvements in Fire-Extinguishing Apparatus, of which the following is a specification, reference being had therein to the accompanying drawing.

10 My invention relates to fire extinguishing apparatus and is especially adapted to "dry pipe" systems and those wherein gas is chemically generated for creating pressure upon a fire extinguishing liquid and thus 15 discharging the latter through suitable outlets.

In the accompanying drawings, Figure 1 is a cross sectional view of a portion of a building equipped with my devices. Fig. 2 is an enlarged detail view, partly in section, 20 showing the lower and gas generating portion of the same devices. Fig. 3 is a section on the line 3-3, Fig. 2.

In these figures, A represents a vertical 25 section of a portion of a common form of building and B a strong reservoir, for liquid, located near the ground and provided with a constantly ascending branched discharge pipe C having its branches C' each provided 30 with a suitable valve C² and adapted for connecting the usual fire hose D. In each of the branches normally rests a weight E, shown as a ball, arranged to be released by opening the corresponding valve so that it 35 may pass down within the pipe by gravity, and by its impact or weight operate devices to be described and thus cause high pressure in the reservoir B. While such devices may be varied in construction and location, they 40 are shown as involving two upwardly open chemical-containers F, eccentrically pivoted at F' so that they normally stand in stable equilibrium. Between their upper adjacent margins is a movable wedge-like or conical 45 member G fixed to a rod G' sliding in a bearing in a diaphragm G², itself fixed in the lower part of the pipe C, and normally sustained by a light spring H interposed 50 between the diaphragm and a plate H' fixed to the upper end of the rod. The bearing is made gas tight under gas tension in the tank by means of a pliable disk I carried by the rod and pressed upward against the diaphragm by the gas below. If any of the 55 valves above be opened, the corresponding weight in the pipe falls by gravity and when

it reaches the plate H' compresses the spring, depresses the wedge, and upsets the containers F, as indicated in dotted lines. The chemicals thus discharged into the tank 60 are such that gas is generated in the usual way creating high pressure upon the liquid in the reservoir. The liquid is thus forced through a pipe J leading from the lower part of the tank into the pipe C at a point 65 above the plate H' and thence passes upward to be discharged through the pipe branch in which the valve was opened.

To avoid dangerous pressure when the 70 opened valve is closed before the generation of gas ceases, a pipe K leads from the upper portion of the pipe C to the open air and is provided with any suitable safety valve K', preferably protected by a suitable housing L.

If the weights be heavy, it is not indispensable to rely upon impact for depressing the wedge, nor the weights necessarily invariable in character, nor is the construction in other respects unchangeable; and I do not, 80 therefore wish to limit the claims to the construction set forth.

What I claim is:

1. In apparatus of the class described, the combination with a standpipe system arranged to provide for free downward passage of actuating weights and connected with a reservoir below, means for releasing weights within the pipes of said system, and means actuated by the weights for causing 85 gas producing chemicals to react and force liquid out of the reservoir into said system.

2. The combination with a reservoir for liquid, of a pipe extending upwardly therefrom and having a distant discharge opening, means for creating gas pressure in the reservoir, a weight normally held at a distance from the reservoir and adapted to fall within said pipe by gravity, means for 90 releasing the weight, and means operated by the descending weight for putting said pressure-creating means into action.

3. The combination with a liquid containing reservoir, of a pipe extending upwardly therefrom and adapted for discharging said liquid at a distant point, a weight within 95 said pipe, normally held in raised position and adapted to fall therein by gravity, means for releasing the weight, and means whereby the released weight causes the generation of gas pressure in the reservoir.

4. The combination with a liquid contain-

ing reservoir, of a pipe extending upwardly therefrom and having an upwardly inclined valve controlled branch at a distance from the reservoir, a weight normally held in said 5 branch and arranged to be released by opening the valve, and means operated by the released weight for creating gas pressure in the reservoir.

5. The combination with a liquid containing 10 reservoir and a pipe leading upwardly therefrom and provided with upwardly inclined valve controlled branches at various heights, of a series of valve released weights normally held in the branches, respectively, 15 and a chemical container arranged to be discharged by any of said weights, in falling, and thereby to create gas pressure in said reservoir.

6. The combination with a liquid containing 20 reservoir and a pipe leading constantly upward therefrom and having a distant valve controlled outlet, a weight normally held in raised position in said pipe by the closed valve, a receptacle for gas producing 25 chemicals located in the reservoir, and means whereby the descending weight, released by opening the valve, causes the discharge of said chemicals into the reservoir.

7. The combination with a reservoir for 30 liquid, of a pipe extending upwardly therefrom and having upwardly inclined branches at different points, valves controlling the

discharge from said branches, respectively, balls normally resting in the branches, respectively, and each arranged to be released 35 by opening the corresponding valve, a chemical container arranged to be discharged into the reservoir by any falling ball, and a discharge pipe leading from the lower part of the reservoir into the pipe first 40 mentioned at some distance from its lower end.

8. The combination with a liquid reservoir and a branched pipe leading continuously upward therefrom, of an eccentrically 45 pivoted upwardly open chemical container within the reservoir, valves controlling the branches of said pipe, respectively, weights normally lying in the branches, respectively, and each arranged to be released by the 50 opening of the corresponding valve, a conduit leading from the upper part of said pipe to the open air and provided with a safety valve, means for chemically creating gas pressure in the reservoir, and means 55 whereby any released weight, in falling, brings the pressure creating means into action.

In testimony whereof I affix my signature in presence of two witnesses.

JOSEPH A. STEINMETZ.
